UNITED STATES PATENT OFFICE.

OTTILIA FALKENBERG, OF BALTIMORE, MARYLAND

GAME-BOARD

No. 866,447.

Specification of Letters Patent. Patented Sept. 17, 1907.

Application filed January 28, 1907. Serial No. 354,443.

To all whom it may concern:

Be it known that I, OTTILIA FALKENBERG, a citizen of the United States, and a resident of the city of Baltimore, in the State of Maryland, have invented a new 5 and Improved Game-Board, of which the following is a full, clear, and exact description.

This invention relates to parlor games, and the object of the invention is to produce a game board for playing a game which will afford amusement and instruction 10 to the players. The game involves the use of a map upon which routes of travel are indicated, and involves also the element of chance, brought into the game by the use of dice.

The invention consists in the construction and combination of parts, to be more fully described hereinafter and particularly set forth in the claims.

Reference is to be had to the accompanying drawings forming a part of this specification, in which similar characters of reference indicate corresponding parts in 20 all the figures.

Figure 1 is a view, representing a board upon which the game is played; Fig. 2 is a plan of a portion of this board upon an enlarged scale, and illustrating further the manner in which the game is played; Fig. 3 is a 25 cross section through the board, taken through one of the routes of travel referred to above, and illustrating a "man" or pin which represents a traveler, and Figs. 4 and 5 represent perspective views of dice which are adapted to be thrown or shaken by the players in carrying on the game.

Referring more particularly to the parts, 1 represents a board upon which the game is played. Upon the face of this board a map is formed, and this map represents the continents of the earth, and seas, as shown. Upon 35 the face of the map routes of travel are indicated leading across the continents and seas and passing through a number of cities or places of interest. These routes of travel are indicated by slots 2 which are cut in the face of the board, as indicated in Figs. 2 and 3. For this 40 purpose, the board is preferably formed of two sheets 3 and 4 superposed upon each other, and held apart at the routes 2 by distance blocks or posts 5. At the cities, enlargements or cut-outs 6 are formed which extend laterally from the routes of travel or slots, for a purpose 45 which will appear more fully hereinafter. In these slots two pins or "men" 7, which represent travelers, are loosely held, said pins being provided with T-heads 8 which are adapted to be inserted in the slots, as indicated in Fig. 3. It should be understood that these 50 "men" are adapted to be applied in the channels so as to represent travelers moving along a route of travel, and they will be advanced from place to place as the game progresses.

Upon the board, as indicated in Fig. 2, near the slot which represents a route of travel, a legend is inscribed, 55 such as the word "caravan," indicating that at this point of the route a traveler would travel by caravan.

Where the route crosses the ocean, the word "steamer" indicates that the passenger would go by this means. In this way, according to the country through which 60 the traveler is passing, the usual means of progress will be indicated on the map. Thus, if the route led into the arctic regions, the mode of travel would be indicated by the word "sled" or similarly. If the route lay through India, where at a certain point it would be 65 necessary to travel by means of elephants, it would be indicated upon the route at this point. If the route was to be covered by means of an automobile, this would be indicated at the appropriate point on the route.

In order to play the game, I provide the dice illustrated in Figs. 4 and 5. These dice are simply cubical blocks, upon the faces of which pictures or illustrations are placed, indicating the different means of travel. Thus on the block represented in Fig. 4 there is illustrated a caravan on one face and a sail boat on an adjacent face; on the block shown in Fig. 5 an elephant is represented on one face, a sled on another and an automobile on the third face. Each of the dice is formed with a blank face, as indicated in Fig. 4, for a purpose 70 75 which will appear hereinafter.

In playing the game, the travelers or pins are expected to travel from the same point and return. The player whose man returns before the others wins the game. The moves to which the different players are 85 entitled are determined by throwing the dice shown in Figs. 4 and 5. Suppose that the traveler belonging to a certain player is located at Bagdad, from which point a traveler may pass only by caravan. The player throws the dice, and should a caravan "be thrown", that is, 90 should the caravan come face up on the die the player may advance his man to the next stopping place. If, however, the player should be unlucky and throw the sail boat uppermost when the die is cast, he would not be able to advance his man and the throw of the dice 95 would pass to the next player.

The different routes on the map would be indicated by different colors, corresponding to the means of progress. Thus the caravan routes would be indicated in red, steamers or sailing vessels in blue, and so on. The 100 cubes or dice have faces representing the modes of travel corresponding to the different countries.

If the player should throw a blank he, of course, loses his turn and the throw of the dice passes as before. If one of the "men" overtakes that of an opponent in 105 another city he is entitled to an extra move. The

players may play as partners or as individuals. In this way a very interesting and instructive game may be played having the element of chance.

Having thus described my invention, I claim as new 5 and desire to secure by Letters Patent:

1. A board having a map with routes of travel indicated thereupon, said routes of travel having different means of travel indicated adjacent thereto and connecting the same cities along said routes, in combination with a 10 chance device having parts representing the different means of travel and "men" adapted to be advanced along said routes, the moves of said "men" being suggested by the said chance device.

2. A board having a map with routes of travel indicated thereupon, and different means of travel indicated 15 respectively adjacent to said routes and connecting certain of the cities on said routes, "men" adapted to be

advanced along said routes, and dice having faces representing the means of travel indicated on different routes, said dice being adapted to be thrown to determine the 20 means of travel which may be given to said "men."

3. A board having a map with routes of travel indicated thereupon, means of travel indicated adjacent to said routes respectively, said routes being formed by slots in said board, "men" running in said slots and adapted 25 to be advanced therein, and dice adapted to be thrown and having faces corresponding to the means of travel indicated on said routes, the throw of said dice determining the amount of advancement to be given to said men.

In testimony whereof I have signed my name to this 30 specification in the presence of two subscribing witnesses.

OTTILIA FALKENBERG.
